DISCHARGE GUIDE

James McIntosh, Pittsburgh, Pa.

Application March 24, 1937, Serial No. 132,827

4 Claims. (Cl. 214—18)

This invention relates to discharge guides, and more particularly those which are adapted for use in removing coke from coke ovens, although not limited thereto.

5 One of the objects of the present invention is to provide a variable length passageway for guiding material from storage bins, ovens or the like, to a second receptacle.

A further object of the invention is to provide 10 a discharge guide of the type described which will prevent the spillage of coke during its passage from a coke oven to a quencher car.

The above and further objects will be made 15 apparent by referring to the following description and the accompanying drawings, in which:

Figure 1 is a plan showing the relation of the guide, under the present invention, to the oven and quencher car;

Figure 2 is a side elevation of the present invention;

Figure 3 is a section on line III—III of Figure 2; and,

Figure 4 is a section on line IV—IV of Figure 2.

Referring more particularly to the accompanying drawings, the numeral 2 indicates a plurality of parallel coke ovens, the ends of which are in substantial alignment. The coke ovens 2 have corresponding charging and discharging ends, and have tracks 4 extending the length of the 30 coke ovens adjacent the discharge ends thereof. A quencher car 6 is carried by the tracks 4 for receiving the coke from the coke ovens 2.

As the quencher car 6 cannot abut the coke ovens 2, due to elements extending varying 35 lengths therefrom, apparatus must be provided to direct the coke which has been pushed from the coke ovens into the quencher car 6. This apparatus comprises a discharge guide 7 which may include a frame 8 mounted on a truck 10.

40 The frame 8 is sturdily constructed and is composed of any suitable material, such as I-beams, angles, or the like. The truck 10 is mounted on wheels 12 which are engaged with a track 14 that extends along the coke ovens 2 adjacent the discharge 45 ends thereof. Of course, the truck 10 and frame 8 form a unit which may be moved along the discharge ends of coke ovens 2. A sleeve or housing 16 is secured to the frame 8 to provide a portion of a passageway between the coke ovens 50 2 and the quencher car 6. The sleeve 16 should be of substantially the same, or slightly larger, cross-section as that of the coke ovens 2, and the walls of the sleeve 16 may be made from metallic plates, if desired. The frame 8 carries

55 a telescoping guide 18 between the sleeve 16 and

the coke ovens 2. The telescoping box-shaped guide 18 is carried on the frame 8 substantially parallel to the coke ovens 2 and in alignment with the sleeve 16 in which it is adapted to be received.

5 The telescoping guide 18 is slidably mounted on the sleeve 16 by any suitable means which may include rail sections 20 carried by the telescoping guide. The rail sections 20 engage with wheels 22 that are journaled on the frame 8.

10 As the telescoping guide 18 is subject to severe stresses and sudden changes in temperature, at least portions of the sides thereof are made from channels 24. The channels are preferably spaced from each other in order to reduce the tendency 15 of the telescoping guide to warp. A substantially U-shaped chute-like member 26 is used to form the bottom and lower side portions of the telescoping guide 18. The member 26 should be stronger and more durable than the remainder 20 of the telescoping guide because it receives more wear and rougher use than the other portions thereof.

Suitable means are provided to move the telescoping guide 18 relative the sleeve 16, such as 25 a motor 28. The shaft of the motor 28 is extended to connect with a speed reducer 29. Rotation of the motor shaft transmits power to a pinion gear 32 carried by a shaft 30 on the speed reducer, said gear 32 being adapted to engage 30 a gear segment 34 secured to a shaft 36. The shaft 36 is suitably journaled on the frame 8 and carries a bell-crank 38. The longer arm of the bell-crank 38 is pivotally secured to one end of a link 40 which is pivotally secured to the telescoping guide 18 to transmit motion thereto. When the motor 28 rotates, the pinion gear 32 is driven, which, in turn, partially rotates the shaft 36 through the medium of the gear segment 34. The partial rotation of the shaft 36 40 causes the bell-crank 38 and the link 40 to change their positions relative to the telescoping guide and produce movement thereof. Upon rotation of the motor shaft in the proper direction, the telescoping guide can be made to move toward 45 or away from the sleeve 16.

Ordinarily, it is highly desirable to actuate the telescoping guide 18 by forces that are applied to corresponding portions on opposite sides thereof. Therefore, the motion of the motor 28 must be 50 transferred to the opposite side of the telescoping guide. For this purpose, I provide a link 42 which is secured to the shorter arm of the bell-crank 38 and to an arm 44 of a shaft 46. The shaft 46 is journaled on the frame 8 and 55

extends across the top of the telescoping guide 18. An arm 48 is carried by the opposite end of the shaft 46, and is connected to an assembly of a link 49, bell-crank 50 and link 51, which 5 are respectively similar to the previously described link 42, bell-crank 38 and link 40. Thus, the motion produced by the motor 28 is transmitted to both sides of the telescoping guide 18.

The telescoping guide carries a stop 54 which 10 is adapted to engage the wheels 22 when the telescoping guide is at either extremity of its limited movement.

An end gate 56 is secured at the end of the sleeve 16 to be placed adjacent the quencher car 6. The end gate 56 can be used to hold coke in the sleeve 16 until a quencher car is provided to receive it therefrom.

The telescoping guide 18 may be substantially longer than the sleeve 16, if desired, and the 20 length of the telescoping guide 18 is such that it can be made to bridge the distance between the sleeve 16 and the discharge end of the coke ovens 2, and also close the gap between quencher car 6 and sleeve 16 when discharging coke. Thus, 25 as one end of the sleeve 16 is positioned so that it can be placed adjacent the quencher car 6, a continuous passage-way can be formed between the discharge end of a coke oven and a quencher car.

30 In most cases, it is advisable to provide suitable controls so that the discharge guide cannot be moved along the coke ovens 2 unless the telescoping guide 18 is positioned within the sleeve 16. By providing such control the apparatus is 35 made to function in such a manner that neither the end of the telescoping guide nor the discharge end of the coke ovens can be damaged when the discharge guide 18 is moved along the coke ovens 2.

30 While I have shown and described one specific embodiment of my invention, it will be understood that various modifications can be made without departing from the scope of the invention as defined by the following claims.

45 I claim:

1. A coke oven discharging device adapted for movement between the discharge end of a row of parallel aligned coke ovens and a quencher car comprising a frame arranged for movement along the row of coke ovens having a chute-like 50 housing member arranged therewith, a movable box-shaped member having a chute disposed in the bottom thereof arranged in said housing member, said box-shaped member adapted to move telescopically of said housing member with the chute in said box-shaped member adapted to cooperate with said housing member so as to provide an extensible chute for discharging and guiding the coke therethrough from any 55 one of the ovens to the quencher car, means for movably supporting and guiding said box-shaped member in its telescopic movement in said housing, and means for moving said box-shaped chute member away from and toward said ovens and normally thereto so as to position the inner end thereof against the oven to be emptied opposite the discharge opening therein.

60 2. A coke oven discharging device adapted for movement between the discharge end of a row

of parallel aligned coke ovens and a quencher car comprising a frame arranged for movement along the row of coke ovens having a chute-like housing member arranged therewith, a movable chute member disposed within said housing member and adapted to move telescopically thereof with the chute member adapted to cooperate with said housing member so as to provide an extensible chute for discharging and guiding the coke therethrough from any one of the ovens to the quencher car, cooperating track and wheel means arranged between said frame and said movable chute member for supporting said movable chute member in said housing member and for guiding the same in its telescopic movement, 10 and means for moving said chute member away from and toward said ovens so as to position the inner end thereof against the oven to be emptied opposite the discharge opening therein.

15 3. A coke oven discharging device adapted for movement between the discharge end of a row of parallel aligned coke ovens and a quencher car comprising a frame arranged for movement along the row of coke ovens having a box-shaped chute-like housing member arranged therewith, a movable box-shaped member having a chute positioned in the bottom thereof arranged in said housing member, said box-shaped chute member adapted to move telescopically of said housing member with the chute in said box-shaped 20 member adapted to cooperate with said housing member so as to provide an extensible chute for discharging and guiding the coke therethrough from any one of the ovens to the quencher car, a rail member attached to each side of said box-shaped chute member adjacent the bottom thereof, said rail members adapted to rest on and cooperate with wheels pivotally arranged on said frame so as to support said box-shaped chute member and guide the same in its telescopic movement into and out of the housing, 25 means arranged on each side of said box-shaped chute member adjacent the upper end thereof which is adapted to cooperate with means carried by the frame to aid in guiding the chute 30 member in its movement, and means for moving said chute member away from and toward said ovens so as to position the inner end thereof against the oven to be emptied opposite the discharge opening therein.

4. A coke oven discharging device adapted for movement along the discharge end of a row of parallel aligned coke ovens comprising a movable supporting means arranged for movement along the row of coke ovens, a chute-like housing member carried by said supporting means, a movable box-shaped member having a chute member disposed in the bottom thereof telescopically arranged within said housing member so as to provide an extensible chute for discharging the coke therethrough from any one of said ovens, said housing member and the chute member in the bottom of said box-shaped member together adapted to provide a continuous chute for guiding the coke therethrough, and means for moving and guiding said box-shaped member into and out of said housing.

JAMES McINTOSH.
